UNITED STATES PATENT OFFICE.

DUNCAN A. MACCUAIG, OF NEBRASKA CITY, NEBRASKA.

CASTER-RETAINING DEVICE.

No. 921,132.

Specification of Letters Patent.

Patented May 11, 1909.

Application filed August 26, 1908. Serial No. 450,331.

To all whom it may concern:

Be it known that I, DUNCAN A. MACCUAIG, a citizen of the United States, residing at Nebraska City, in the county of Otoe and State of Nebraska, have invented a new and useful Caster-Retaining Device, of which the following is a specification.

The primary object of the present invention is to provide a retaining device particularly useful in connection with casters for metal beds, and the like, though not necessarily limited to such use, and which is simple, inexpensive and very effective in its holding action.

A further object is to provide a retaining device, which can be employed in connection with an ordinary caster pintle, is provided with a plurality of bearing elements, and is sufficiently yieldable to enter a socket and pass any obstructions or roughness due to irregularities in the walls of the socket.

Several embodiments of the invention are disclosed in the accompanying drawings, wherein:—

Figure 1 is a perspective view of a caster, showing one form of the retaining device applied thereto. Fig. 2 is a vertical longitudinal sectional view through the caster. Fig. 3 is a perspective view of the retaining device *per se*. Fig. 4 is a horizontal sectional view on the line 4—4 of Fig. 2. Fig. 5 is a perspective view of a caster showing a slightly modified form of retaining device thereon. Fig. 6 is a longitudinal sectional view through the structure disclosed in Fig. 5. Fig. 7 is a perspective view of the retaining device removed from the caster. Fig. 8 is a top plan view of the structure disclosed in Fig. 5. Fig. 9 is a perspective view of still another embodiment of the invention. Fig. 10 is a detail perspective view of the wire element of the retaining device disclosed in Fig. 9. Fig. 11 is a cross sectional view through the structure disclosed in Fig. 9. Fig. 12 is a detail vertical sectional view substantially on the line 12—12 of Fig. 11.

Similar reference numerals designate corresponding parts in all the figures of the drawings.

Referring first to the embodiment disclosed in Figs. 1—4 inclusive, a caster pintle 13 is employed, which is secured at its lower end to the usual yoke 14, in which the roller 15 is journaled. A washer 16 is located over

the connection between the said pintle and yoke, while another washer 17 is located upon the free end of the pintle 13, and is held against detachment thereon by upsetting said end, as illustrated at 18. Interposed between the washers 16 and 17 is the retaining device, which is formed from a single piece of wire bent into the form disclosed in Fig. 3. That is to say, oppositely disposed open sided loops 19 surround the outer end of the pintle just beneath the washer 17, and correspondingly shaped loops 20 surround the inner end of the pintle adjacent to the washer 16. It will be noted that these sets of loops are disposed in angular relation, that is to say, the closed ends of the loops 19 engage different sides of the pintle 13 to those engaged by the closed ends of the loops 20. Connecting the ends of the loops 19 and 20 are retaining arms 21, which are thus disposed longitudinally of the pintle in spaced relation to the same, and on different sides thereof. It will be evident that this retaining device is exceedingly simple in its character, and can be cheaply manufactured, and applied to a caster pintle. It is securely retained in place, however, and has sufficient yielding action to permit the caster to be applied to an article of furniture, as it will readily enter the socket to receive it. When in position, however, it properly centers the caster pintle in the socket, and inasmuch as it has four arms 21 that engage the walls of the socket, the caster will be effectively held in position.

A slightly different form of construction is disclosed in Figs. 5—8 inclusive. In this embodiment of the invention the caster pintle, which is designated 22, has opposite outstanding lugs 23 formed upon its free end. The retaining device is formed from a single piece of wire, and in general outline corresponds to the above described embodiment of the invention, that is to say, it is provided with an upper set of oppositely disposed loops 24 arranged in overlapping relation and a lower set of oppositely disposed loops 25 also arranged in overlapping relation. The loops of the different sets are connected by retaining arms 26 disposed longitudinally of the pintle 22 in spaced relation to said pintle. In this construction, however, it will be noted that the uppermost loop 24 has its opposite sides pinched substantially together, as shown at 27, forming practically a closed loop that abuts against the projections or 110

lugs 23 and prevents the detachment of the retaining device from the pintle. This structure operates the same as and has all the advantages of the first described embodiment.

5 In Figs. 9-12 inclusive, still another form of construction is disclosed. In this embodiment, the caster pintle 28 has an enlarged upper end 29. The retaining device comprises a body formed of a single piece of wire having upper oppositely disposed loops 30 and 31, which surround the upper end of the pintle and are arranged in overlapping relation beneath the enlarged portion 29 of said pintle. The upper loop 30 has its opposite side pinched inwardly as shown at 32 to form a substantially closed loop, which abuts against the enlargement 29 and prevents the detachment of the retaining device. The other loop 34 has an open side. Connected 10 to the ends of these loops are retaining arms 33 which are disposed longitudinally of the pintle 28 in spaced relation to the same and on opposite sides thereof. The lower ends of these arms are connected by cross rods 34 15 arranged on opposite sides of the pintle and engaging in the hooked terminals 35 of a strap 36 located on the pintle 28. This strap takes the place of the lower sets of loops employed in the other forms of construction, 20 but it will be noted that the plurality of bearing arms, together with the upper set of loops is still present. No claims are made to the specific structure of this embodiment of the invention as the same constitutes the 25 subject-matter of a separate application, filed simultaneously herewith, Serial No. 450,332.

From the foregoing, it is thought that the construction, operation and many advantages of the herein described invention will be apparent to those skilled in the art, without further description and it will be understood that various changes in the size, shape, proportion and minor details of construction, 40 may be resorted to without departing from the spirit or sacrificing any of the advantages of the invention.

Having thus fully described my invention, what I claim as new, and desire to secure by 45 Letters Patent, is:—

1. The combination with a caster pintle, of a caster retaining device formed of a wire looped about the pintle and having retaining arms disposed substantially lengthwise of 50 said pintle.

2. The combination with a caster pintle,

of a caster retaining device formed of a wire and including adjacent loops extending in opposite directions about the pintle and having retaining arms disposed longitudinally of said pintle. 60

3. The combination with a caster pintle, of a retaining device formed of a single piece of wire having overlapping oppositely disposed loops that extend in opposite directions about the pintle, and retaining devices carried by the loops and located in spaced relation to the pintle. 65

4. The combination with a caster pintle, of a roller mounted on one end thereof, overlapping loops extending around the free end of the pintle, the outer of said loops being substantially closed, the inner loop having an open side, and retaining arms carried by the loops and extending lengthwise of the pintle. 70

5. The combination with a caster pintle, of a retaining device comprising wire loops engaging the ends of the pintle, and retaining arms connecting said loops. 75

6. The combination with a caster pintle, of a retaining device comprising spaced sets of oppositely disposed loops that surround the pintle, and retaining arms connecting said sets. 80

7. The combination with a caster pintle, of a retaining device comprising spaced sets of oppositely disposed loops that surround the pintle, the loops of one set being disposed in angular relation to the loops of the other set, and retaining arms connecting said sets and disposed longitudinally of the pintle in spaced relation thereto. 85

8. The combination with a caster pintle, of a retaining device formed of a single piece of wire and comprising sets of oppositely disposed loops surrounding the ends of the pintle, the loops of one set having their closed ends engaging different sides of the pintle to those engaged by the closed ends of the loops of the other set, and retaining arms 90 connecting the ends of the loops of one set with the ends of the loops of the other set, said arms being disposed longitudinally of the pintle on opposite sides thereof, and in spaced relation thereto. 95

In testimony, that I claim the foregoing as my own, I have hereto affixed my signature in the presence of two witnesses.

DUNCAN A. MACCUAIG.
